PUMP

Walter Czarnecki and Wesley Czarnecki, Eddington, Pa., assignors, by mesne assignments, to Eddington Metal Specialty Co., Eddington, Pa., a firm

Application June 13, 1936, Serial No. 85,098

1 Claim. (Cl. 103—136)

This invention relates to pumps such as are commonly employed for the purpose of building up pressure in a fluid, and the invention is concerned primarily with pumps of the so-called 5 rotary type.

The invention has in view, as its foremost objective, the provision of a rotary pump, which includes a rotor that is eccentrically mounted in a circular pump housing, and which rotor carries 10 blades which are movable with respect thereto.

Another somewhat more detailed object of the invention lies in the provision of a pump of the character above noted, which includes mechanical means for positively causing movement of the 15 blades with respect to the rotor. In carrying out this idea in a practical embodiment, appropriate cam surfaces are associated with the blade, whereby rotation of the rotor which carries the blades renders effective the cam surfaces to cause the desired relative movement between the blades 20 and rotor.

Yet another object of the present invention is the provision of a pump, of the type above noted, in which suitable ducts are provided in the pump parts to cause lubrication thereof, and inasmuch 25 as these pumps ordinarily are designed for the pumping of fuel oil, the invention contemplates the use of the oil which is being put through the pump as the source of supply of the lubricant.

The invention has in view, as a further objective, the provision of a pump of the character above described, which includes a rotor and blades carried thereby, and with which blades cooperate the mechanical means for positively 30 causing movement of the blades, and in addition certain spring elements which are associated with the blade, and which obviate the need for highly accurate machining of these parts.

A further object of the invention is to provide 40 a rotary pump of the character above noted, in which pressure is built up in the fluid with a so-called double action, that is the fluid is subjected to two pumping operations and actions which are independently identifiable.

More particularly this invention contemplates 45 an arrangement in which the rotor carrying the blades is mounted in a housing which is shaped to cooperate with the rotor in defining two distinct pumping chambers. Communication between these chambers is established by suitable passageways formed in the housing. As the rotor is rotated the blades carried thereby move in the usual manner, and affect the fluid in one chamber to build up pressure therein.

The fluid in this condition passes over through

the passageways in the housing to the other chamber, where the operation of the rotor continues to build up the pressure. With this so-called double action on the pump, a desired pressure is built up much more quickly than would otherwise be the case. 5

Various other more detailed objects and advantages will in part become apparent, and in part be hereinafter stated, as several embodiments of the invention are illustrated and described. 10

The invention, therefore, comprises a rotary pump, including a rotor which is eccentrically mounted in the housing, and which rotor carries a plurality of blades that are movable with respect to the rotor. Mechanical means are provided for causing movement of the blades with respect to the rotor, and in addition certain spring means are employed for causing proper positioning of the blades with respect to the 20 housing. 20

Suitable ducts are provided throughout the parts for insuring of the proper lubrication thereof from the fluid which is having pressure built up thereon by the pump. 25

For a full and more complete understanding of the invention, reference may be had to the following description and accompanying drawings wherein—

Figure 1 is a longitudinal section through a 30 rotary pump assembly, made in accordance with the precepts of this invention.

Figure 2 is a transverse section, taken at right-angles to the showing of Figure 1. This view is taken about on the plane represented by the 35 line 2—2 of Figure 1.

Figure 3 is a fragmentary detailed showing in perspective of the cap element per se.

Figure 4 is another fragmentary detailed showing, bringing out the construction of one of the 40 parts which is associated with the rotor.

Figure 5 is a detailed view in elevation of the rotor, together with the driving shaft on which it is mounted.

Figure 6 is a detailed view in perspective of 45 one of the blades.

Figure 7 is an end elevational showing of a somewhat modified form, in which the blades are carried in a spiral arrangement by the rotor.

Figure 8 is a side elevational showing of the 50 rotor having the spiral blades.

Figure 9 is a detailed perspective view of one of the blade elements per se, which is shown in Figures 7 and 8.

Figure 10 is a detailed view in perspective of

one of the blade elements in a somewhat modified form, in which the blade elements are formed with recesses for receiving cam ribs, which are carried by other parts of the assembly.

5 Figure 11 is a view similar to Figure 3, but of the modification in which the blades of Figure 10 are used, likewise,

10 Figure 12 is a perspective view similar to Figure 4, of the modification shown in Figures 10 and 11,

15 Figure 13 is a perspective view similar to Figures 3 and 11, with still another modification in which cam surfaces are provided for causing movement of the blade in one direction only,

20 Figure 14 is a view similar to Figures 4 and 12, corresponding to the modification shown in Figure 13,

25 Figure 15 is a detailed perspective view of the blade element with the modification of Figures 13 and 14,

30 Figure 16 is a transverse section, taken through still another modification in which springs are included in the blade assembly,

35 Figure 17 is a perspective view of the various parts of a blade assembly in a somewhat exploded relationship, and

40 Figure 18 is a transverse section taken through a modification in which the so-called double action is provided.

45 Referring now to the drawings, wherein like reference characters denote corresponding parts, it is first noted that the pump assembly herein illustrated and described is designed for the purpose of building up pressure on fluids when occasion demands. Under numerous conditions of usage, oil will be the fluid on which the pressure is built up, and the invention is, therefore, herein set forth as used in conjunction with such a fluid which is effective to lubricate the parts.

50 Obviously the invention is susceptible of use on other fluids, in which case a different lubricating arrangement would be provided.

55 Referring now to Figure 1, a pump housing is referred to generally by the reference character H and is shown as formed with ears 10, which may be availed of in mounting the pump in any desired operative position. Forwardly of the ears 10, the housing H is formed with a cylindrical bore 11, which is defined by a wall 12 that is slightly enlarged in thickness as indicated at 13.

60 As brought out more clearly in Figure 2, the thickened portion 13 is formed with a pair of passages 14 and 15, which communicate with the cylindrical bore 11. At their extremities the passages 14 and 15 may be threaded, as shown at 16 and 17, respectively, to provide for properly connecting suitable conduits thereto.

65 Received in the inner portion of the cylindrical bore 11 is a bearing sleeve 18, which may be fitted in the bore 11 as by a pressed fit. This bearing sleeve 18 is formed with a cylindrical bore 19, which is eccentric to the cylindrical bore 11; that is the axis of the cylindrical bore 19 is out of alignment with the axis of the bore 11.

70 75 Figure 1 shows a drive shaft 20 extends into the housing H, and is formed with a slightly thickened portion 21, that is received in the bore 19. Forwardly of the sleeve 18 this drive shaft 20 carries the rotor assembly in a manner to be hereinafter described. Rearwardly of the sleeve 18, the drive shaft 20 extends through a chamber 22, which is defined by a wall 23, constituting a part of the housing H.

As shown in Figure 1, a bearing member 24 is formed with a cylindrical opening 25, through

which the shaft 20 extends, and this bearing member 24 constitutes a cap for closing the chamber 22. The bearing member 24 may be held in position in any preferred manner, as by a screw fastening means, indicated at 26.

The cylindrical opening 25 in the bearing member 24 may be slightly enlarged, as shown at 27, to provide a recess for receiving a packing member 28. The latter may be held in position by a ring, shown at 29.

Inasmuch as the fluid which is being affected by the present pump is put under high pressure on one side of the pump housing, as will be later described, it is important to guard against leakage of the fluid along the shaft 20. Accordingly 15 a packing gland is shown at 30, as being drivably carried by the shaft 20, in any preferred manner, such as by the pin shown at 31.

This packing gland 30 is formed with a nose at 32, which engages the sleeve 18 adjacent to the 20 enlarged portion 21 of the shaft. The packing gland 30 also carries a packing ring 33, which is disposed about the shaft 20, and which is held in position in the packing gland 30 by a retaining ring 34, formed with a tubular extension 35, which 25 extends into a coil spring 36.

The coil spring 36, at its other end, receives a corresponding tubular projection 37, formed on a retaining ring 38, which maintains a packing ring 39 in assembled position within another 30 packing gland 40. This packing gland 40 is also drivably mounted on the shaft 20, in any preferred manner, and has a nose at 41 which engages against the bearing member 24.

It is evident that the spring 36 affects the pack- 35 ing glands 30 and 40 to cause the noses 32 and 41 to effectively engage the sleeve 18 and bearing member 24, respectively, so as to prevent leakage of fluid past these surfaces in engagement.

At the same time leakage directly along the 40 shaft 20 is checked by the packing rings 33 and 39, which function is further supplemented by the packing ring 28, which is carried by the cap 24.

Forwardly of the sleeve 18 the shaft 20 is enlarged in diameter to provide a rotor 42, and which rotor is formed with a plurality of radially extending slots 43. At its forward end the shaft 20 is reduced in diameter, as indicated at 44, and the reduced portion 44 is received in a recess 45, 50 formed in a front cap member 46. This cap member 46 may be retained in position in the front portion of the housing in any preferred manner, as by the bolts indicated at 47.

As shown in Figure 1, packing means, such as 55 a gasket 48, may be interposed between the cap member 46 and wall 13 of the housing H. It is notable that the axis defining the recess 45 is in substantial alignment with the axis of the cylindrical bore 19 in the sleeve 18, and is, therefore, 60 eccentric with respect to the cylindrical bore 11.

The cap member 46 is formed with an eccentric flange 50 that extends into the bore 11, and a circular groove 51 is formed in the end surface of the flange 50, this circular groove being eccentric 65 with respect to the axis of the recess 45, but substantially coaxial with the cylindrical bore 11.

The sleeve 18 is also formed with a circular groove 52, which corresponds to the circular 70 groove 51 in that it is eccentric to the axis of the bore 19 of this sleeve 18, but coaxial with the bore 11.

Received in each of the slots 43 is a blade element 53, which is formed at each extremity with 75

projections 54, which extend into the grooves 51 and 52, respectively.

The operation of the above described pump assembly may be briefly described by noting, first, that the cap member 46, and sleeve 18 are immovably mounted in the housing H, so that as the rotor 42 is rotated incident to driving of the shaft 20, the blades 43 will be caused to move radially inwardly and outwardly, as the case may be, due to the engagement of the projections 54 in the eccentric grooves 51 and 52.

The respective position of the blades 53 with respect to the rotor and housing is clearly brought out in Figure 2. The blade, in the uppermost position, is fully received in the slot 43, and does not project beyond the cylindrical surface 49 of the rotor 42, while the blade 53, at the bottom, is in its fully extended position in which it projects beyond the cylindrical wall 49, and engages the cylindrical bore 11.

As fluid is admitted into the passageway 16 it is effected by rotation of the rotor 20 in the direction indicated by the arrow, to build up pressure on the fluid as it is driven outwardly through the passageway 15.

As above pointed out, the fluid on which pressure is being built up may be oil, and provision for lubricating the relatively moving parts from this fluid, as a source of supply, may be made by providing the cap member 46 with a duct 55, which communicates from the exterior wall of the flange 50 to the recess 45.

The drive shaft 20 and rotor 42 are also formed with a duct 56 which extends from the extremity 35 of the reduced end 44, in the recess 45, to a point just rearwardly of the rotor 42, and substantially axially of the shaft 20, this duct 56 then extends radially outwardly to a groove 57, which is formed in the enlarged portion 21 of the shaft 20.

Lubricant in the form of a fluid, as driven in the pump, may pass through the ducts 55 and 56, as well as the groove 57, to insure of proper lubrication of the relatively movable parts.

Referring now more particularly to Figures 10, 11 and 12, a somewhat modified form is shown in which the flange 50 of the cap member 46 is formed with an eccentric rib 58, rather than a recess. Likewise, the bearing sleeve 18 is formed with an eccentric rib 59, which corresponds to the rib 58 on the cap member 46. In this modification of the invention, blades 60 are employed, which are formed with recesses 61, which are designed to receive the ribs 58 and 59. The proper radial movement of the blades 60 is caused by the interengagement between the eccentric ribs 58 and 59 in the recesses 61.

In this form of the invention it is notable that a duct 62 extends from the free face of the rib 58 to the duct 55, this being brought out clearly in Figure 11.

Yet another form of the invention is shown in Figures 7, 8 and 9, in which blades 63 are shown as being of a spiral construction, and arranged in correspondingly spirally formed slots 64 in the rotor 42. When this spiral arrangement of the blades is used, it is notable that the surfaces of the blades 63 have a curvature, as indicated at 65, this to insure of providing a good surface engagement with the cylindrical bore 11.

Referring now more particularly to Figures 13, 14 and 15, still another modification of the invention is shown in these views. The flange 50 of the cap 46 is shown as formed with an eccentric surface at 66, while the sleeve 18 is formed 75 with a corresponding cam surface 67. A blade,

of a somewhat different construction, is shown in Figure 15, at 68, and this blade 68 is formed at each side with a notch which provides a surface 69, which is adapted to engage the cam surfaces 66 and 67, inclusive.

It is evident that an engagement of the cam surfaces 66 and 67 with the surfaces 69 of the blade 68 will cause proper outward lateral movement of the blades 68. Inward movement of these blades may be caused by engagement thereof with the cylindrical bore 11.

In the forms of the invention above described, accurate machining of the blade elements and the surfaces which they engage is at least a highly desirable factor, and in order to obviate the need for such great accuracy, the invention proposes the use of still another modification which is brought out in Figures 16 and 17. In these views each of the recesses 43 receives a blade assembly which is referred to generally by 15 the reference character A. Such a blade assembly comprises a main body portion 70, which is formed at each end with a projection 71 that is adapted to be received in the eccentric grooves 51 and 52 respectively.

The main body portion 70 is formed on each side with extensions 72, and at the bottom of these extensions 72 with a pair of openings, as indicated at 73. Received in each of the openings 73 is a coil spring 74, and bearing against the opening 73, and contained between the side extension 72 is a second blade element 75.

In the form of the invention shown in Figures 16 and 17, it is notable that a certain amount of mechanical movement of the blade assembly A 35 is caused by the fitting of the projections 71 in the eccentric grooves 51 and 52. At the same time assurance of proper engagement of the blade element 75 with the cylindrical bore 11 is provided at all times, due to the presence of the 40 spring members 74.

Referring now to Figure 18, still another modification is shown in which the housing assumes a shape different from that shown in the other forms of the invention. In Figure 18 the housing 45 is referred to as 76, and is shown as formed with a central opening 77, which has a vertical dimension substantially equal to the diametrical dimension of the rotor 42. However, the horizontal dimension of the opening 77 is considerably in 50 excess of the diametrical dimension of the rotor 42, and as a result two pumping chambers are defined by the rotor 42, together with the housing 76. These chambers are referred to as 78 and 79, and it is noted that they are of a crescent-like formation.

The housing 76 is formed with an inlet opening at 80, which communicates with the chamber 78, and an outlet opening at 81, which communicates with the chamber 79. Communication between 60 the chambers 78 and 79 is provided by the vertical passages 82 and 83, and a cross passage 84.

As the rotor 42 is rotated in the direction of the arrow, the blades carried by the rotor affect the fluid in the chamber 78 to build up pressure 65 therein. The fluid under the condition of this built up pressure passes through the passageways 82, 84 and 83 to the chamber 79, where it is again affected by the rotor 42 and the blades carried thereby, to build up further pressure, after which 70 it is discharged through the opening at 81.

It is evident that this double chamber arrangement provides for a so-called double action on the part of the pump, in that the fluid is subjected to two more or less distinct pumping opera-

tions, and as a result any desired degree of pressure can be built up much more quickly than would be the case were the single action type of pump employed.

5 While preferred specific embodiments of the invention are hereinbefore set forth, it is to be clearly understood that we are not to be limited to the exact constructions illustrated and described, because various modifications of these 10 details may be provided in putting the invention into practice within the purview of the appended claim.

We claim:

15 A rotary pump of the character described comprising a housing formed with a cylindrical bore, a bearing sleeve in said bore, a cap for the housing having a flange extending into the bore, a drive shaft formed with a rotor which is received

in the bore by the said cap and bearing sleeve, said cap being formed with a recess which receives the extremity of the drive shaft, said cap also being formed with a lubricating duct extending from said recess to the exterior wall of said 5 flange surface, a duct in the drive shaft extending from the free end of the recess to the portion of the drive shaft which is received in the bearing sleeve, and another duct extending from said last mentioned duct to the surface of said drive 10 shaft, said rotor being formed with a plurality of slots, blades movable in said slots, and cam means carried by said sleeve and flange portion of the cap respectively, for causing movement of said blades incident to rotation of the rotor. 15
